UNITED STATES PATENT OFFICE.

WILLIAM H. FAUBER, OF CHICAGO, ILLINOIS.

DOOR-BELL.

SPECIFICATION forming part of Letters Patent No. 396,993, dated January 29, 1889.

Application filed August 30, 1888. Serial No. 284,120. (No model.)

To all whom it may concern:

Be it known that I, WILLIAM H. FAUBER, residing at Chicago, in the county of Cook and State of Illinois, and a citizen of the 5 United States, have invented a new and useful Improvement in Door-Bells, of which the following is a specification, reference being had to the accompanying drawings, in which—

Figure 1 is a central vertical section. Fig. 10 2 is an end view of the tube which contains most of the operating devices, showing also the devices which are in view. Fig. 3 is a section at line 3 of Fig. 1. Fig. 4 is a plan of the strikers and block to which they are 15 secured. Fig. 5 is a side view of the slotted plate, the movement of which operates the strikers. Fig. 6 is a central vertical section showing how the strikers can be operated by pulling instead of pushing. Fig. 7 is a detail, 20 being a side elevation of the casting B shown in Fig. 6.

This invention has for its object to improve door-bells and their operating mechanism of the type known as "gongs;" and the invention 25 consists in the novel features of construction and combination of devices hereinafter described and claimed.

In the drawings, A represents a wall by the side of an outside door.

30 a is a hole through the wall A.

B is a casting secured to the inside of A, which casting has a tubular part, b, which is to be inserted in the hole a.

C is a gong supported on the arm c, which, 35 as shown, is an extension of the inner end of the tube, said arm and tube being integral with the casting B and extending horizontally therefrom in opposite directions.

d d' are two strikers, one of which only is 40 seen in Fig. 1. The inner ends of these strikers are secured to a block, e, which is pivoted in the tube b on a pivot, f.

g is a pin secured to the block e, and extending outward therefrom a short distance toward the center of the tube.

h is a plate provided with a slot the opposite walls of which are zigzagged.

j is an ear on the plate h, which ear is provided with a screw-threaded hole.

50 k is a push-rod provided, as shown, with a screw-thread, by means of which it is connected with the ear j, and can be adjusted as

may be necessary on account of different thicknesses of walls.

l is a push-button on the outer end of the 55 rod k.

m is a support and guard for the push-button.

n is a coiled spring to return the push-rod 60 and plate h to place.

The operation is as follows: By pushing in the push-button l the sliding plate h will be moved toward the bell, and the walls of the slot, passing over the pin g, will rock the block e on its pivot f and rapidly vibrate the strikers, 65 which, of course, are to be arranged so that when vibrated they will come in contact with the gong. As shown, the push-rod k is supposed to pass through the hole in the casting B; but it is not necessary that this push-rod 70 should be as long as shown in the drawings. A single striker may be used; but I prefer two.

In Fig. 6 I have shown a modification, by the use of which the strikers can be operated by a pulling movement instead of a pushing 75 movement, the push-button being dispensed with.

As shown in Figs. 6 and 7, the wall of the casting B is provided with a notch having two inclined walls, u u', and the operating-rod v 80 is secured at one end to the ear j, and the other end passes up through a hole in the casting B, and is then bent over and down between the two walls u u' of the notch in this casting B.

In Fig. 6 the casting B and bell may be supposed to be located upon a wall, E, in a room of some distance from the outside door. A wire can be secured to the outer end, w, of the rod v, and thence carried to the outside 90 door and there be operated by a bell-pull, intermediate bell-crank levers and other devices being used, as is common for pull-bells.

In the modification shown in Fig. 6 the strikers are operated by the movement of the 95 slotted plate h the same as in Fig. 1. The passage of the bent end of the rod v over either wall of the notch in B will cause the slotted plate h to move over the pin g the same as before described. The position of the bell and casting B may be such that there will be a direct outward pull on the bent-over end of the rod v, instead of an angular pull, the effect being the same.

It is not intended that the bent-over end of the rod *v* will be arranged so as to pass at the same time over both of the walls *u u'*, but the arrangement of the bell may be such that such rod will pass over either one of such walls.

5 What I claim as new, and desire to secure by Letters Patent, is as follows:

1. The casting *B*, formed integral with the oppositely-projecting tube *b* and arm *c*, and 10 the gong *C*, mounted on the arm, in combination with the block *e*, pivoted inside the tube, and having the pin *g* and a striker, and a 15 lengthwise-movable rod extending into the tube, and provided therein with an attached plate, *h*, having a slot, *i*, provided with a zigzagged wall, and into which slot projects the pin on the pivoted block, substantially as described.

2. The combination, with a gong, *C*, and a 20 casting, *B*, having a tube, *b*, of the block *e*, pivoted in the tube, and having the pin *g* and a striker, and a lengthwise-movable rod extending into the tube, and having an attached 25 plate, *h*, in the tube, provided with a slot, *i*, having a zigzagged wall, substantially as described.

3. The combination, with a gong, *C*, and a 30 casting, *B*, having a tube, *b*, of the block *e*, pivoted in the tube, and having the pin *g* and a striker, the plate *h*, located in the tube, and

having an ear, *j*, and a slot, *i*, provided with a zigzagged wall, and a lengthwise-movable rod engaging said ear to move the slotted plate, substantially as described.

4. The combination, with a gong, *C*, and a 35 casting, *B*, having a tube, *b*, of the block *e*, pivoted within the tube, and provided with a pin, *g*, and a striker, a plate, *h*, in the tube, having an ear, *j*, and a slot, *i*, provided with a zigzagged wall, and a push-rod, *k*, extending 40 through the tube and engaging the ear to move the slotted plate, substantially as described.

5. The combination, with a base-plate, *B*, having the oppositely-projecting tube *b* and 45 arm *c*, of the gong *C* on the arm, the block *e*, pivoted on the tube, and provided with a pin, *g*, and a striker, the plate *h*, having a slot, *i*, provided with a zigzagged wall, and an ear, *j*, provided with a screw-threaded orifice, and the push-rod *k*, having a screw-thread engaging the orifice in the ear, for operating the slotted plate and adapting the parts to different thicknesses of walls, substantially as described.

WILLIAM H. FAUBER.
